ERNEST R. GODWARD, OF INVERCARGILL, NEW ZEALAND.

SURFACE VAPORIZER ATTACHMENT FOR CARBURETERS.

1,383,932.

Specification of Letters Patent.

Patented July 5, 1921.

Application filed April 30, 1920. Serial No. 377,796.

To all whom it may concern:

Be it known that I, ERNEST R. GODWARD, a subject of the King of Great Britain, residing at Invercargill, New Zealand, have 5 invented certain new and useful Improvements in Surface Vaporizer Attachments for Carbureters; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15 The present invention relates, generally, to carbureters; and the invention has reference, more particularly, to an improved construction of surface vaporizer attachment for carbureters. 20 The invention has for its principal object to provide a novel construction of surface vaporizing device adapted to be connected with a carbureter to receive the mixture of liquid fuel and air therefrom; said surface 25 vaporizing device being so constructed that it will provide a maximum area of surface arranged within a limited bulk or space, and which is further arranged to support, carry and spread the liquid portions of the fuel 30 mixture in a manner allowing time for the liquid fuel to completely evaporate before final discharge to the engine cylinders.

The invention has for a further object to provide a construction of surface vaporizer 35 which will gage and control the amount of fuel mixture to be operated upon, so that only such an amount is allowed to enter which can be evaporated by the device.

The invention has for a still further object 40 to provide a surface vaporizing device operating upon the general principles disclosed in my prior Patent No. 1,291,833, with the added improving feature that the evaporating surface is provided by a plurality of nested cone-shaped plates or disks 45 inclining downwardly in the direction of movement of the fuel mixture whereby the liquid fuel cannot fall or run back toward the inlet of the device, but must move, if at 50 all, toward the outlet of the device, thus permitting gravity to assist in the spreading and thinning out of the liquid fuel upon the evaporating surface.

Other objects of the present invention,

not at this time more particularly enumerated will be clearly understood from the following detailed description of the same.

The invention is clearly illustrated in the accompanying drawings, in which:—

Figure 1 is a vertical longitudinal section 60 of the novel surface vaporizer device for carbureters made according to and embodying the principles of my present invention; and Fig. 2 is a horizontal cross-section 65 through the same, taken on line 2—2 in said Fig. 1.

Similar characters of reference are employed in all of the hereinabove described views, to indicate corresponding parts.

Referring now to said drawings, the reference-character 1 indicates the upper section of a casing, and 2 indicates the lower section of said casing. Said lower casing section is provided with an inlet opening 3. Secured to said lower casing section, by 70 means of bolts 4, or other suitable fastening means, is the discharge end 5 of a carbureter, so arranged as to be connected in communication with said inlet opening 3. Disposed within the interior bottom of said casing 75 section 2 so as to surround said inlet opening 3 is an internally threaded boss 6 to which is secured a conical base member 7 having a central opening 8 corresponding to and alined with said inlet opening 3. 80

The reference-character 9 indicates a plurality of truncated conical disks or plates which are each provided with a central opening preferably equivalent in diameter to the diameter of said inlet opening 3. Said conical disks or plates 9 are nested together one 85 above another in a vertical pile, and have their central openings vertically alined to provide an inlet passage 3' extending upwardly through the pile from the inlet opening 3. Said conical disks or plates 9 are slightly spaced apart one from another to provide intermediate lateral passages 10. The spacing of said disks or plates 9 bears a definite relation to the cross-sectional area 90 of the inlet passage 3', whereby the combined area of the inner or intake ends of said passages 10 is approximately equivalent to the area of the mouth of the inlet passage 3', thus the intake ends of said passages 10 together with the inlet passage 3 serve as a definite gage to control the amount 95 of fuel mixture which may be drawn through 100

the passages 10, said amount being only that which the disk or plate surfaces, contiguous to said passages 10, can successfully evaporate. The said conical disks or plates provide, contiguous to said passage 10, downwardly and outwardly inclined surfaces extending from the intake ends of said passages 10 to the outlet ends thereof, said surfaces increasing in area from said intake 10 toward said outlet ends of said passages.

Said lower casing section 2 is provided with a discharge opening 11 approximately equivalent in diameter or cross-sectional area to that of said inlet passage 3'. Supported in connection with said lower casing section 2 concentric to said pile of disks or plates 9, and so as to surround the latter, is an inner wall 12 tapering upwardly so as to provide in communication with the outlet 20 ends of said passages 10 an outlet passage 13 gradually increasing in cross-sectional area toward the bottom of said pile of disks or plates, said outlet passage 13 being in communication with said discharge opening 25 11. Supported upon the upper end of said inner wall 12 is a cap member 14 closing over the pile of disks or plates 9, and provided with a central depending hollow inverted conical member 15 which projects 30 downwardly into said inlet passage 3' so as to terminate substantially opposite the bottom of said pile of disks or plates 9. The inclined walls of said conical member 15 serve to reduce the cubic area of said inlet 35 passage 3' from the bottom thereof upwardly, so that the charge of fuel mixture entering said inlet passage 3' and thence into the passages 10 between the disks or plates 9 is deflected readily into said passages 10, and, furthermore, by the cubic area 40 reduction of the inlet passage 3' serving to compensate for the reduction of the volume of the said charge as it is successively taken into the passages 10 while ascending said inlet passage 3'.

The upper section 1 of said casing is supported upon the lower section 2 so as to surround and extend over the pile of plates or disks 9 inclosed within the inner wall 12 50 and cap member 14, being spaced from the latter members so as to provide a jacketing passage or chamber 16. Said upper casing section 1 is provided with an intake passage 17 and an outlet passage 18 suitably disposed to communicate with and serve said jacketing passage or chamber 16. Said jacketing passage or chamber is adapted to receive, for circulation therethrough a heating medium, such as hot air or the exhaust gases 55 of an internal combustion engine, thereby serving to maintain a temperature within the passages of the vaporizer adapted to assist the volatilizing and evaporating processes exercised thereby upon the fuel mixture 60 passed therethrough.

In operation my novel surface vaporizer is connected between a carbureter and the intake manifold leading to the cylinders of an internal combustion engine. The carbureter serves to produce a fuel mixture, comprising, for example, intermingled air and gasoline, which is discharged from said carbureter to flow through said surface vaporizer under the pull of the induction strokes of the engine pistons. The charge of fuel mixture is thus caused to enter said inlet passage 3' and from thence into and through the passages 10 provided by said pile of spaced disks or plates 9. Having entered the intake ends of said passages 10, the charge proceeds therethrough toward the outlet ends thereof, and, by reason of the increase in circumference, and consequently of the capacity of said passages 10 toward their outlet ends the velocity of the air (in 75 and by which the liquid particles of the fuel mixture are carried and supported) is checked or decreased so that the particles of liquid fuel which have not already been absorbed by the air, drop, by gravity, out of 80 the air stream and are deposited upon the lower contiguous surface of the disks or plates 9 bounding said passages. Since the surface area of said plates or disks 9 also increases toward the outer circumference of 85 the latter, the said particles of liquid fuel are spread out on such increasing surface in an increasingly attenuated layer or film, under the pull of the moving air stream, and are therefore so thinned out as to be rapidly 90 evaporated and again taken up into the air stream to unite therewith and form the explosive mixture discharged from the device for delivery to the engine cylinders. Since 95 the surfaces of said disks or plates 9 are inclined downwardly toward the outlet ends of said passages 10, the spreading out and thinning of the liquid fuel on said surfaces is also assisted by the pull of gravity, and the movement of the liquid fuel is constantly 100 toward the discharge end of the device, and, furthermore, the liquid fuel cannot run back to the inlet passage 3' or return in any degree or form to the carbureter.

I am aware that some changes may be 115 made in the arrangements and combinations of the various devices and parts, as well as in the details of the construction of the same, without departing from the scope of my present invention as set forth in the 120 foregoing specification and as defined in the appended claims. Hence, I do not limit my invention to the exact arrangements and combinations of the various devices and parts as described in said specification, nor do I 125 confine myself to the exact details of the construction of said parts as illustrated in the accompanying drawings.

I claim:—

1. In a device of the kind described, a cas- 130

- ing having an inlet opening and a discharge opening, a plurality of nested conical plates inclosed within said casing, said conical plates being vertically separated to provide 5 intermediate lateral passages bounded by the downwardly and outwardly sloping surfaces of contiguous plates, said plates having centrally disposed openings of uniform diameter alined together to provide an inlet passage 10 between the intake ends of said lateral passages and said inlet opening of said casing, and the walls of said casing being spaced away from the outer circumference of said nested plates to provide an annular 15 discharge passage between the outlet ends of said lateral passages and said discharge opening of said casing.
2. In a device of the kind described, a casing having an inlet opening and a discharge opening, a plurality of nested conical plates inclosed within said casing, said conical plates having centrally disposed openings of uniform diameter alined together to provide an inlet passage extending through said 20 nested plates and communicating with said inlet opening of said casing, said conical plates being vertically spaced one from another to provide intermediate lateral passages bounded by the downwardly sloping 25 surfaces of contiguous plates, the distance of separation of said plates being such that the sum of the areas of the intake ends of said lateral passages approximates the cross-sectional area of said inlet passage extending 30 through said plates, and the walls of said casing being spaced away from the outer circumference of said nested plates to provide an annular discharge passage between the outlet ends of said lateral passages and said 35 discharge opening of said casing.
3. In a device of the kind described, a casing having an inlet opening and a discharge opening, a plurality of nested conical plates inclosed within said casing, said conical plates having centrally disposed openings of uniform diameter alined together to provide an inlet passage extending through said nested plates and communicating with said inlet opening of said casing, said conical 40 plates being vertically spaced one from another to provide intermediate lateral passages bounded by the downwardly sloping surfaces of contiguous plates, the distance of separation of said plates being such that the 45 sum of the areas of the intake ends of said lateral passages approximates the cross-sectional area of said inlet passage extending through said plates, and the walls of said casing being spaced away from the outer circumference of said nested plates to provide an annular discharge passage between the outlet ends of said lateral passages and said discharge opening of said casing, and an inverted conical member extending downwardly through said inlet passage of said 50 casing having an inlet opening in its bottom end and a laterally extending discharge opening, a conical base-member secured within said casing, said base member having a central opening alined with said inlet opening of said casing, a vertical pile of nested conical plates supported on said base member, said plates having vertically alined central openings of uniform diameter providing an inlet passage through said pile of plates, said plates being vertically separated to provide intermediate lateral passages bounded by the downwardly and outwardly sloping surfaces of contiguous plates, an inner annular wall surrounding said pile of plates and spaced therefrom to provide an annular discharge passage in communication between said lateral passages and said discharge opening of said casing, a cap member supported by said inner annular wall to extend over said pile of plates, and said cap member having an inverted conical member projecting downwardly through said inlet passage of said pile of plates.
5. In a device of the kind described, a casing having an inlet opening in its bottom end and a laterally extending discharge opening, a conical base-member secured within said casing, said base-member having a central opening alined with said inlet opening of said casing, a vertical pile of nested conical plates supported on said base-member, said plates having vertically alined central openings of uniform diameter providing an inlet passage through said pile of plates, said plates being vertically separated to provide intermediate lateral passages bounded by the downwardly and outwardly sloping surfaces of contiguous plates, an inner annular wall surrounding said pile of plates and spaced therefrom to provide an annular discharge passage in communication between said lateral passages and said discharge opening of said casing, a cap member supported by said inner annular wall to extend over said pile of plates, said cap-member having an inverted conical member projecting downwardly through said inlet passage of said pile of plates, and an upper casing section inclosing said annular wall and cap member in spaced relation therefrom to provide a jacketing chamber, said upper casing section having inlet and discharge openings communicating with said jacketing chamber.
6. A surface vaporizing attachment for carbureters in which a maximum of surface

area is provided in small bulk, comprising a pile of nested conical plates having central openings alined together to provide an inlet passage adapted to receive a fuel mixture through its lower end, said nested conical plates being vertically spaced one from another to provide lateral passages between said plates leading outwardly and downwardly from said inlet passage, and means 5 having a discharge opening adapted to inclose said pile of plates so as to receive the vaporized fuel mixture passing out of said lateral passages, said conical plates providing downwardly and outwardly inclined 10 fuel supporting surfaces contiguous to said lateral passages which increase in area from the intake ends toward the outlet ends of the latter whereby the fuel assisted by gravity may spread out thereupon so as to 15 be easily evaporated.

7. A surface vaporizing attachment for carbureters in which a maximum of surface area is provided in small bulk, comprising a pile of nested conical plates having central 25 openings of uniform size alined together to provide an inlet passage to receive a fuel mixture through its lower end, said nested conical plates being vertically spaced one from another to provide lateral passages be- 30 tween said plates leading outwardly and downwardly from said inlet passages, the distance of separation of said plates being such that the sum of the areas of the intake ends of said lateral passages approximates the cross-sectional area of said inlet passage, and means having a discharge opening adapted to inclose said pile of plates so as to receive the vaporized fuel mixture passing out of 35 said lateral passages, said conical plates providing downwardly and outwardly inclined fuel supporting surfaces contiguous to said lateral passages which increase in area from the intake toward the outlet ends of the latter whereby the fuel 40 assisted by gravity may spread out thereupon so as to be easily evaporated and an inverted conical member extending downwardly through said inlet passage of said nested plates adapted to progressively reduce the cubic area of said inlet passage in the direction of flow of a fuel charge there- 45 through proportionally to the volume reduction of a fuel charge as it is successively taken into said lateral passages intermediate 50 said nested plates.

8. A surface vaporizing attachment for carbureters in which a maximum of surface area is provided in small bulk, comprising a pile of nested conical plates having central 55 openings of uniform size alined together to provide an inlet passage to receive a fuel mixture through its lower end, said nested conical plates being vertically spaced one from another to provide lateral passages between 60 said plates leading outwardly and downwardly from said inlet passage, the distance of separation of said plates being such that the sum of the areas of the intake ends of said lateral passages approximates the cross-sectional area of said inlet passage, and means having a discharge opening adapted to inclose said pile of plates so as to receive the vaporized fuel mixture passing out of 65 said lateral passages, said conical plates providing downwardly and outwardly inclined fuel supporting surfaces contiguous to said lateral passages which increase in area from the intake toward the outlet ends of the latter whereby the fuel assisted by gravity may 70 spread out thereupon so as to be easily evaporated and an inverted conical member extending downwardly through said inlet passage of said nested plates adapted to progressively reduce the cubic area of said inlet passage in the direction of flow of a fuel charge there- 75 through proportionally to the volume reduction of a fuel charge as it is successively taken into said lateral passages intermediate said nested plates.

In testimony that I claim the invention set forth above I have hereunto set my hand this 28th day of April, 1920.

ERNEST R. GODWARD.
